UNITED STATES PATENT OFFICE.

JOHN CLULEE, OF WALLINGFORD, CONNECTICUT, ASSIGNOR TO THE SIMPSON, HALL, MILLER & COMPANY, OF SAME PLACE.

DESIGN FOR A HANDLE FOR SPOONS, FORKS, &c.

SPECIFICATION forming part of Design No. 29,215, dated August 16, 1898.

Application filed July 25, 1898. Serial No. 686,853. Term of patent 7 years.

To all whom it may concern:

Be it known that I, JOHN CLULEE, of Wallingford, in the county of New Haven and State of Connecticut, have invented and produced a new Design for a Handle for Spoons, Forks, and Similar Articles; and I do hereby declare the following, when taken in connection with the accompanying drawings and the letters of reference marked thereon, to be a full, clear, and exact description of the same, and which said drawing constitutes part of this specification, and represents a face view of a handle embodying my design.

This invention relates to the design for a handle for spoons, forks, and similar articles of table-service; and the design consists in the configuration and ornamentation of the handle, as hereinafter described, and shown in the accompanying illustration.

As herein shown, the lower portion of the handle contracts slightly, as at A, then gradually expands to about half the length of the handle, as at B, then curves outward and in-

ward, following the contour of a series of scrolls, as at C, then gradually expands in a series of longer scrolls D toward the top of the handle, which is surmounted by a scroll-and-shell ornament E, which the configuration of the handle follows. These scrolls forming the outline of the handle inclose a plain panel F, which is slightly raised, and extends, contracted to follow the contour of the handle, throughout its length, all as shown in the accompanying illustration.

I claim—

The design for a handle for spoons, forks and similar articles as herein shown and described.

In testimony whereof I have signed this specification in the presence of two subscribing witnesses.

JOHN CLULEE.
